UNITED STATES PATENT OFFICE.

JOHN W. BENEDICT, OF HASTINGS, MICHIGAN.

KEYHOLE-GUARD.

958,849.

Specification of Letters Patent. Patented May 24, 1910.

Application filed February 23, 1909. Serial No. 479,377.

To all whom it may concern:

Be it known that I, JOHN W. BENEDICT, a citizen of the United States, residing at Hastings, in the county of Barry and State 5 of Michigan, have invented a new and useful Improvement in Keyhole-Guards, of which the following is a specification.

This invention relates to a shield designed to protect locks against picking, either by 10 means of skeleton keys, or by the insertion of any instrument for the purpose of dislodging the original key, thus clearing the keyhole for the insertion of a false key.

The invention consists in providing the 15 lock with a transversely arranged squared shaft carrying two steel guard plates working within the lock casing and covering the keyhole the inner guard plate being provided with a keyhole slot so that the key 20 may be inserted from either side of the door for rotating said shaft, said rotation being prevented when the key is in the slot of the inner guard plate.

In the accompanying drawings, Figure 1 25 is a vertical section through the lock casing, showing the locking and guard mechanism in elevation. Fig. 2 is a sectional end view. Fig. 3 is a perspective view of the shaft. Figs. 4 and 5 are detail face views of the inner and outer guard plates, respectively.

In these drawings, 1 represents the lock casing having the usual spring pressed catch 2 and a key operated bolt 3. Tumblers 4 of the usual kind are also provided. Fitting 35 transversely across the casing 1 and arranged between the mechanism of the catch 2 and the inner end of the bolt 3 is a squared shaft 5 into the ends of which are threaded rotatable pins 6 having upon their outer 40 ends milled heads 7 said heads being respectively upon the inner and outer sides of the door. Fitted upon the squared shaft adjacent the outer wall of the casing, but within the casing is a solid keyhole guard plate 8. Fitted upon the opposite end of the squared 45 shaft and adjacent the inner wall of the casing is a plate 9 having a keyhole slot 10. A suitable key 11 for operating the tumblers 4 is adapted to pass through the slot 10.

The plates 8 and 9 are parallel to each other and when the shaft 5 is rotated so that the slot 10 will register with the regular keyhole slot of the lock the plate 8 will cover the keyhole in the outer face of the casing 1. The key can then be inserted

from inside, but no key or instrument for tampering with the lock can be inserted in the lock casing through the keyhole opening upon the outside of the door. Nor can the shaft 5 be rotated from either side of the door for the purpose of causing the shields to clear the keyhole while the key 60 11 is in the lock as the said key passes through plate 9 thus locking the shaft against rotation. But at the same time if 65 the occupant of the house or room locks the door from the outside he can turn the plate 8, after withdrawing the key from the lock to cover the keyhole, and upon return can readily by means of the outer milled head 70 7 swing the guard 8 out of the way, insert the key and open the door. After again withdrawing the key he can turn the plates 8 and 9 back into normal position and upon locking the door from the inside, the key 75 passing through the slot 10, the guard plate 8 will again be locked into position closing the keyhole from the outer side.

Upon the bottom of the lock casing I form upwardly extending lugs 12 and the 80 lower ends of the guard plates work between said lugs and the side walls of the lock casing, and the lugs by bearing upon the inner faces of the plates 8 and 9, respectively, prevent their being bent inwardly 85 or otherwise sprung out of position.

What I claim is:—

1. The combination with a lock casing, of a squared shaft means for rotating said shaft, and guard plates fixed upon said shaft and covering the keyhole when in normal position, one of said plates having a keyhole slot formed therein.

2. The combination with a lock casing, a squared shaft transversely arranged in said casing, pins threaded into the ends of said shaft, milled heads on said pins, the heads being respectively upon the outer and inner faces of a door a non-perforated guard plate fixed upon the outer end of the squared shaft 95 and normally covering the keyhole, and a slotted plate fixed upon the inner end of the squared shaft, the slot of said plate lining with the keyhole and admitting a key from the inner side of the door, as and 100 for the purpose set forth.

3. In a lock having a spring catch and a key operated bolt, a squared shaft arranged transversely between the spring catch and bolt operating mechanism, means 110

- operable from either side of the door for
rotating said shaft, and guard plates fixed
upon opposite ends of the squared shaft,
and simultaneously covering the keyhole,
5 the plate adjacent the inner side of the door
having a keyhole slot therein adapted to
register when the plate is in normal posi-
tion with the keyhole of the door.
4. In a lock a squared shaft, pins passing
10 transversely through the door and lock cas-
ing and entering the ends of said shaft,
turning means carried by said pins, a solid
guard plate fixed upon the squared end of
the shaft adjacent the outer side of the lock
15 casing, a plate having a keyhole slot therein
fixed upon the inner end of the squared
shaft and working adjacent the inner side
of the lock casing, and lugs formed upon
the bottom of the lock casing and bearing

respectively upon the inner faces of said 20
plates.

5. A device of the character described
comprising a rectangular bar having cy-
lindrical bearing portions adjacent to each
25 end, and a plate rigidly secured on each
end of said bar, the plate on the outer end
of said bar entirely covering the keyhole
in the door, the plate on the inner end of
the bar having an opening therein register-
ing with the keyhole adapted to receive a 30
key, the positioning of the key in the lock
preventing the rotation of said bar and
plates.

JOHN W. BENEDICT.
